US00D762181S

(12) **United States Design Patent**
Lin

(10) **Patent No.:** US D762,181 S
(45) **Date of Patent:** ** Jul. 26, 2016

(54) **HIGH BAY LED DEVICE**

- (71) Applicant: **Aeonovalite Technologies, Inc.**, New Taipei (TW)
- (72) Inventor: **Chhiu-Tsu Lin**, Sycamore, IL (US)
- (73) Assignee: **Aeonovalite Technologies, Inc.**, New Taipei (TW)

(**) Term: **14 Years**

(21) Appl. No.: **29/508,907**

(22) Filed: **Nov. 12, 2014**

CLAIM

The ornamental design for a high bay LED device, as shown and described.

DESCRIPTION

FIG. 1 is a front, top, and side perspective view of the invention.

FIG. 2 is a front elevation view thereof;

FIG. 3 is a side elevation view thereof;

FIG. 4 is a top plan view thereof; and,

FIG. 5 is a bottom plan view thereof.

The features shown in broken lines are shown for illustrative purposes only and form no part of the claimed design in their respective embodiment.

1 Claim, 5 Drawing Sheets
